Patented Sept. 14, 1926.

UNITED STATES PATENT OFFICE.

CHARLES GAY, OF NEW HAVEN, CONNECTICUT.

PORTABLE SACRAMENTAL AND DEVOTIONAL ALTAR.

Application filed February 14, 1924. Serial No. 692,931.

My invention relates to a portable altar of a character to adapt it for sacramental and devotional purposes in the home, hospital, or by missionaries, and particularly relates to an altar comprising a cabinet equipped with a crucifix, candlesticks, and the appurtenances for administering the sacraments of baptism, communion, and extreme 5 unction.

The general object of my invention is to provide a portable cabinet altar outfit which may readily be erected in form for general private devotional purposes in the home or at public worship by a priest when on a mission, or assembled for sacramental use in pastoral sick calls in the home or when carried by the priest to the sick as when on a mission and when so carried in portable form on missions without the character of 10 15 20 the cabinet outfit being disclosed.

The nature of my invention, its distinguishing features and advantages will clearly appear as the description proceeds.

Reference is to be had to the accompanying drawings forming a part of this specification, it being understood that the drawings are merely illustrative of one example 25 30 35 of the invention.

Figure 1 is a front elevation of a portable altar embodying my invention showing the same set up in open position;

Figure 2 is a front elevation of the altar in closed form;

Figure 3 is a transverse vertical section 35 as indicated by the line 3—3, Figure 2;

Figure 4 is a horizontal section in the plane indicated by the line 4—4, Figure 2;

Figure 5 is a detail of the door latch in the unfastened position of the doors;

Figure 6 is a detail showing in rear elevation a hanger that may be employed to suspend the cabinet on a wall or the like;

Figure 7 is a perspective view of a napkin forming part of the altar outfit for sacramental purposes;

Figure 8 is a perspective view of an envelope partly broken away to show the cotton therein forming part of the altar outfit;

Figure 9 is a plan view of one of the right and left-hand self-locking devices for holding the doors of the cabinet open in fixed position while the altar is in use;

Figure 10 is a horizontal section taken through the top piece 21 at the retainers 23 55 when the cross is held by said retainers, the

plane of the section being indicated by the line a—a in Figure 3.

In carrying out my invention in practice in accordance with the illustrated example, a cabinet 10 is provided having a pair of 60 doors 11 at the front swingable on vertical hinges 12. The doors 11 are formed with flanges 13 at the outer sides of the doors and at the top and bottom, said flanges being complementary to and in the plane of 65 the sides and top and bottom of the cabinet 10 and suitable latch means are provided for the door, there being a drop handle 14 on one door and a swingable hook latch 15 pivoted to the opposite door by a screw 16 70 or the like. On the back of the cabinet at the top I may provide as shown a hanger 17 pivoted as at 18 and having a hole 19 that may be disposed above the cabinet to engage a nail or the like on a wall or similar 75 support. For the carrying of the cabinet I have shown a drop handle 20 secured to the top thereof to fold down onto the top when the handle is not in use or to be raised to a vertical position for the carrying of the 80 cabinet to the sick for the use of a priest on a sick call visit, and by priests who serve on missions. An ornamental top piece 21 is provided in practice and detachably held to the cabinet by one or more pins 121 which 85 permit the detachment of the piece 21 and its erection within the cabinet in like manner when the cabinet can, if desired, be closed.

The crucifix 22 of my novel altar assem- 90 blage may have means to suspend it in the cabinet or to hold it erect in the cabinet or upon the top of the same. In the illustrated example the lower end of the crucifix 22 is adapted to be received in angular retainers 95 23 provided on the back of the top piece 21, said retainers being covered with rubber tubing to prevent marring of the cross. I provide a hole or holes in the cabinet cor- 100 responding with the position of the pin or pins 121 so that said top piece may be dis- 105 posed on top of the cabinet at the front. Pin holes are similarly provided in the bottom of the cabinet 10 near the front, so that said top piece may be positioned as shown in Figure 3 within the cabinet and holding the cross as shown, the lower end of the cross resting on the bottom of the cabinet.

I have also shown the crucifix 22 as 110 equipped with a hanger 25 held by a screw

125 or the like, said hanger being adapted to engage a hook 26 depending from the under surface of the cabinet top.

5 A candle or candles being the necessary equipment of an altar, I provide for supporting candlesticks in a manner for their effective disposition when the altar is set up in the open position and at the same time make provision for the proper accommodation 10 of the candlesticks in the closed cabinet. For the stated purpose I provide shelves 27 on the doors 11 at the inner sides and candlesticks 28 on said shelves. The shelves and their supported candlesticks are so positioned 15 that with the swinging of the doors 11 to the closed position the shelves and candlesticks without candles will have clearance at the sides of the crucifix 22 and will be accommodated in the cabinet without interference 20 with the crucifix. At the same time with the opening of the doors the candlesticks are displayed in attractive and efficient positions at the sides of the crucifix when the same is disposed suspended in the cabinet or after the crucifix has been erected inside 25 of the cabinet or on top of the cabinet. When the crucifix 22 is erected within the cabinet at the front thereof and supported by the top piece 21 and the retaining elements 23 thereon, if the arms of the crucifix are made in practice so low as to be in a plane adjacent the top of the candlesticks 28, then the candles *b* may be removed and placed in the cabinet in any convenient location 30 as for example standing in the ablution cup 33.

In order to hold the doors 11 in fixed open positions, I provide right and left hand door holding devices 29 each swivelled at one end to a door, said devices at the opposite ends having a hook formation as at 30. The devices 29 have sliding movement in staples 130 depending from the cabinet top and when the cabinet is swung to the open position the devices 29 have turning movement in the staples 130, the hooks 30 on the devices 29 finally effecting such an engagement with the staples 130 as to hold the doors against accidental closing movement.

55 A communion plate 32 is provided as a necessary part of the outfit and in order that the communion plate may be conveniently stored and readily accessible and at the same time contribute materially to the appearance of the altar I support said communion plate in a vertical plane against the back of the cabinet 10 on small hook-like brackets 31 covered with rubber tubing to 60 protect the surface of the plate 32 disposed on the cabinet back at opposite sides of the vertical medial line. Thus, the communion plate forms an ornamental ground area at the back of the crucifix when suspended in 65 the cabinet.

With a view to complete the outfit for sacramental purposes an ablution cup 33 is provided and a holy water bottle 34 as well as a spoon 35. Furthermore, one or more napkins 36 are provided as well as an envelope 37 containing cotton 38 for sacramental purposes. All the appurtenances of the 70 altar are stored within the closed cabinet and with the doors closed and latched, the cabinet may readily be carried by the handle 75 20 on missions and on sick-calls without the character or the purpose of the cabinet being disclosed.

I would state in conclusion that while the illustrated example constitutes a practical 80 embodiment of my invention, I do not limit myself strictly to the exact details herein illustrated, since, manifestly, the same can be considerably varied without departure 85 from the spirit of the invention as defined in the appended claims.

Having thus described my invention, I claim:

1. A portable altar adapted for devotional and sacramental purposes, said altar comprising 90 a cabinet having a pair of doors hinged to the front portions of the sides of the cabinet, a crucifix having dimensions to be accommodated in said cabinet, means whereby to support said crucifix disposed in 95 vertical position in the cabinet and in spaced relation to the front, back and sides thereof, shelves on the cabinet doors at the inside, and candlesticks on said shelves, said shelves and candlesticks having clearance in the 100 cabinet at the sides of the crucifix for the swinging of the doors to the closed and open positions.

2. A portable altar adapted for devotional and sacramental purposes, said altar comprising 105 a cabinet, swing doors on the cabinet, a crucifix having dimensions to be accommodated in said cabinet, and means to support said crucifix vertically disposed in the cabinet and in spaced relation to the front, 110 back and sides thereof; together with a communion plate, and means to support said communion plate on the back of the cabinet disposed as a back ground behind said crucifix.

3. A portable altar adapted for devotional and sacramental purposes, said altar comprising 115 a cabinet having a pair of doors hinged to the front portions of the sides of the cabinet, a crucifix having dimensions to 120 be accommodated in said cabinet, means whereby to support said crucifix disposed in vertical position in the cabinet and in spaced relation to the front, back and sides thereof, shelves on the cabinet doors at the 125 inside, and candlesticks on said shelves, said shelves and candlesticks having clearance in the cabinet at the sides of the crucifix for the swinging of the doors to the closed and open positions, said shelves positioned in 130

planes above the bottom of the cabinet at an elevation to provide storage space in the cabinet below said shelves at opposite sides of the crucifix.

5. 4. A portable altar for devotional and sacramental purposes, said altar comprising a cabinet, a crucifix, an element having

means to hold said crucifix in upright position, and coacting means on the cabinet and on said element to detachably secure said element to the cabinet top or to the bottom of the cabinet at the interior.

CHARLES GAY.
